UNITED STATES PATENT OFFICE.

JOHN E. SCHENCK, OF CHICAGO, ILLINOIS, ASSIGNOR TO AMERICAN CAN COMPANY, OF NEW YORK, N. Y., A CORPORATION OF NEW JERSEY.

CAN-BODY-MAKING MACHINE.

1,082,559.

Specification of Letters Patent.

Patented Dec. 30, 1913.

Application filed April 8, 1910. Serial No. 554,179.

To all whom it may concern:

Be it known that I, JOHN E. SCHENCK, a citizen of the United States, residing in Chicago, in the county of Cook and State of Illinois, have invented a new and useful Improvement in Can-Body-Making Machines, of which the following is a specification.

My invention relates to improvements in can body making machines.

10 The object of my invention is to provide a can body making machine by means of which necked-in can bodies may be produced.

15 A further object is to provide a machine which will not only operate to form the can body and neck in one end thereof, but also form a seaming flange upon the other end of the can body when desired.

20 My invention consists in the novel construction of parts and devices and in the novel combinations of parts and devices herein shown and described and more particularly specified in the claims.

25 In the accompanying drawing forming a part of this specification, Figure 1 is a side elevation of a can body making and necking-in machine embodying my invention, only that portion of the can body making machine to which my invention particularly

30 relates being shown in the drawing. Fig. 2 is an end elevation. Fig. 3 is a horizontal section on line 3—3 of Fig. 2. Fig. 4 is an enlarged detail sectional view, similar to the lower portion of Fig. 3, but showing the parts in another position to better illustrate the operation. Fig. 5 is a section on line 5—5 of Fig. 4. Fig. 6 is a detail elevation of part of a body forming mechanism. Fig.

35 Fig. 7 illustrates a modification in which a plain supporting head for the outer end of the can body is substituted for the flanging die. Fig. 8 shows a modification in which a plain plunger is substituted for the necking-in plunger or die, and Fig. 9 illustrates a

40 further modification in which a flanging die is substituted for the necking-in die, so that flanges may be produced, if desired, upon both ends of the can body.

45 In the drawing, 1 represents the frame of the machine, the same being of any suitable construction, to give support and mounting to the other parts.

50 2 is the former horn of the can body making machine, the same being preferably of the expandible type. 3 are the folding or

5 forming wings by which the flat blank is wrapped around the horn, 4 the bumper and 5 the reciprocating slide by which the flat blanks from which the can bodies are formed are fed first to the edge folding or 60 hook forming devices and then to the body former horn and then discharged from the body former horn. 6 is an operating shaft of the machine having a crank, 7 for operating the bumper. All these parts are or may 65 be of any suitable kind or construction now commonly in use and familiar and well known to those skilled in the art, and consequently need no further description. The body former horn 2 is preferably furnished 70 with a continuation or extension 8 which may be integral with or in a separate piece from and secured to the end of the body former horn 2, as may be desired, in order that the can body necking-in and flanging 75 mechanism may not be inconveniently close or adjacent to the body former mechanism of the machine.

80 As the can bodies are discharged one by one from the body former horn 2 by the ejector finger 9 of the feed slide 5, they are pushed onto one of the series of necking-in mandrels 10 mounted upon an intermittently revolving turret or carrier 11, which operates to bring a mandrel 10 first into registry 85 or line with a necking in plunger or die 12 carried by a reciprocating stem or slide 13, mounted in suitable guides or bearings 14 on the frame of the machine and reciprocated in unison with the feed slide 5 by a cam 15 on the bumper operating shaft 6 through a connecting lever 16, having a roller 17 traveling in the groove of the cam 15, and which has a slotted yoke connection 18 with the necking-in plunger slide or 90 stem 13.

95 The mandrel turret or carrier 11 is or may be provided with a series of flanging dies 19, one for each necking-in mandrel 10 so that the stroke of the necking-in plunger 100 or die 12 will simultaneously with the necking-in operation also form a flange α upon the outer end of the can body X. Each of the flanging dies 19 has an annular stop shoulder 20 to limit the length of the flange 105 α formed upon the end of the can body. Each of the necking-in mandrels 10 is furnished with an end portion 21 of reduced diameter, and a shoulder 22 between the smaller and larger portions of the necking- 110

in mandrel. Each of the necking-in mandrels 10 is also provided with a slot 23 to receive the reciprocating ejector blade 24 by which the necked-in can body is discharged from the mandrel after the reciprocating necking-in plunger die 12 has been retracted and the turret or carrier given a further partial turn to enable the can body to be ejected from the mandrel without striking or interfering with the necking-in plunger 12. Each of the ejectors 24 is provided with an operating stem 25, having a head 26 and provided with a spring 27 which holds the ejector 24 normally in its retracted position. The ejectors are reciprocated as the turret or carrier 11 revolves by engagement with a stationary cam 28 attached to the frame of the machine. The necking-in die or plunger 12 has a bevel mouth 29 to facilitate the entrance of the end of the can body within the reducing portion 30 of the die. The necking-in mandrel and flanging die carrier 11 is preferably intermittently rotated and locked in position to cause one of its mandrels to accurately register with the body former horn in position to receive a can body therefrom and another of its mandrels to accurately register with the necking-in die or plunger 12 by means of a Geneva stop movement, the same comprising a disk 31, having radial slots 32 and circularly curved notches 33 in connection with a segment disk 34 on the shaft 35 and crank arm 36 having a wrist pin 37 for entering the radial slots.

The shaft 35 is continuously driven from a cross shaft 38 of the body former mechanism through intermittent beveled gears 39, 40.

40 If it is not desired to flange one end of the can body as well as to neck-in the other end thereof, the flanging die 19 is replaced by a plain supporting head 41, as shown in Fig. 7. And if it is desired to simply flange one end of the can body without necking-in the other, the necking-in die or plunger is omitted and a plain plunger 42, as illustrated in Fig. 8, is substituted in the place thereof. And if it is desired to flange both ends of the can body instead of flanging one end and necking-in the other, the flanging die 43, as illustrated in Fig. 9 is substituted for the necking-in die 12.

I claim:

55 1. In a can body machine, the combination with a can body former horn, of a single reciprocating necking-in die or plunger, a plurality of necking-in mandrels and an intermittently moving carrier for moving said mandrels first into register with the body former horn and subsequently into register with said necking-in plunger, said mandrels being stationary relatively to the carrier, and a feed slide for delivering the can bodies from the body former horn onto

the necking-in mandrels, substantially as specified.

2. In a can body machine, the combination with a can body former horn, of a reciprocating necking-in die or plunger, a plurality of necking-in mandrels and an intermittently moving carrier for moving said mandrels first into register with the body former horn and subsequently into register with said necking-in plunger, a feed slide for delivering the can bodies from the body former horn onto the necking-in mandrels, and each of said necking-in mandrels having a can body ejector, substantially as specified.

3. In a can body machine, the combination with a can body former horn, of a single reciprocating necking-in die or plunger, a plurality of non-expansible necking-in mandrels and an intermittently moving carrier for moving said mandrels first into register with the body former horn and subsequently into register with said necking-in plunger, a feed slide for delivering the can bodies from the body former horn onto the necking-in mandrels, each of said necking-in mandrels having a can body ejector within the mandrel, and a stationary cam for operating said can body ejectors as the mandrel carrier rotates, substantially as specified.

4. In a can body machine, the combination with a can body former horn, of a reciprocating necking-in die or plunger, a plurality of necking-in mandrels and an intermittently moving carrier for moving said mandrels first into register with the body former horn and subsequently into register with said necking-in plunger, and a feed slide for delivering the can bodies from the body former horn onto the necking-in mandrels, each of said mandrels having also a flanging die, substantially as specified.

5. In a can body making machine, the combination with a body former horn, of a die reciprocating parallel to said horn, a plurality of mandrels adapted to be brought successively into register with said horn and die, and an intermittently moving carrier upon which said mandrels are mounted, said mandrels being rigidly mounted on the carrier, substantially as specified.

6. In a can body making machine, the combination with a body former horn, of a die reciprocating parallel to said horn, a plurality of non-expansible mandrels adapted to be brought successively into register with said horn and die, and an intermittently moving carrier upon which said mandrels are mounted, each of said mandrels having also a flanging die, substantially as specified.

7. In a can body making machine, the combination with a body former horn, of a die reciprocating parallel to said horn, an

intermittently movable carrier, a plurality of mandrels mounted on said carrier and fixed with respect thereto, means for moving said carrier to thereby bring said mandrels successively first into register with said horn and then with the reciprocating die, and a plurality of can ejectors, one with each of said mandrels, substantially as specified.

8. In a can body machine, the combination with a body former horn, of a reciprocating plunger parallel to said horn, an intermittently movable carrier, a series of mandrels having necking-in and flanging dies thereon mounted on said carrier, and means for moving said carrier to bring said mandrels successively into alinement with said horn and said plunger, substantially as specified.

9. In a can body machine, the combination with a body former horn, of a reciprocating plunger parallel to said horn and

having an external necking-in die thereon, an intermittently movable carrier, a plurality of mandrels mounted on said carrier, each of said mandrels having an internal ²⁵ necking-in die and a flanging die, substantially as specified.

10. In a can body machine, the combination with a body former horn, of a reciprocating plunger parallel to said horn, an intermittently movable carrier, a series of mandrels carried by said carrier, each of said mandrels having a flanging die thereon, and means for moving said carrier to bring the mandrels successively into alinement ³⁰ ²⁵ with the horn and the reciprocating plunger, substantially as specified.

Correction in Letters Patent No. 1,082,559

It is hereby certified that in Letters Patent No. 1,082,559, granted December 30, 1913, upon the application of John E. Schenck, of Chicago, Illinois, for an improvement in "Can-Body-Making Machines," an error appears in the printed specification requiring correction as follows: Page 1, lines 19-20, for the word "constructure" read *construction*; and that the said Letters Patent should be read with this correction therein that the same may conform to the record of the case in the Patent Office.

Signed and sealed this 27th day of January, A. D., 1914.

J. T. NEWTON,
Acting Commissioner of Patents.

intermittently movable carrier, a plurality of mandrels mounted on said carrier and fixed with respect thereto, means for moving said carrier to thereby bring said mandrels successively first into register with said horn and then with the reciprocating die, and a plurality of can ejectors, one with each of said mandrels, substantially as specified.

8. In a can body machine, the combination with a body former horn, of a reciprocating plunger parallel to said horn, an intermittently movable carrier, a series of mandrels having necking-in and flanging dies thereon mounted on said carrier, and means for moving said carrier to bring said mandrels successively into alinement with said horn and said plunger, substantially as specified.

9. In a can body machine, the combination with a body former horn, of a reciprocating plunger parallel to said horn and

having an external necking-in die thereon, an intermittently movable carrier, a plurality of mandrels mounted on said carrier, each of said mandrels having an internal ²⁵ necking-in die and a flanging die, substantially as specified.

10. In a can body machine, the combination with a body former horn, of a reciprocating plunger parallel to said horn, an intermittently movable carrier, a series of mandrels carried by said carrier, each of said mandrels having a flanging die thereon, and means for moving said carrier to bring the mandrels successively into alinement ³⁰ ²⁵ with the horn and the reciprocating plunger, substantially as specified.
